UNITED STATES PATENT OFFICE.

BENJAMIN H. WRIGHT, OF ROME, NEW YORK.

STEAM-BOILER.

Specification of Letters Patent No. 28,032, dated April 24, 1860.

To all whom it may concern:

Be it known that I, B. H. WRIGHT, of Rome, Oneida county, and State of New York, have invented a new and useful 5 Steam-Boiler; and I do hereby declare that the following, taken in connection with the drawings making part thereof, is a full, clear, and exact description of my invention.

The drawing is a longitudinal vertical section through the boiler. My boiler has been devised under the impression, that a non-circulating boiler or one in which there is a very slight circulation is the best, and I have essayed with considerable success, as 10 my experiments prove, to construct a boiler in which the water shall progress gradually from the point or points at which it is injected by the feed pumps and become more and more heated in its progress until 15 it at last flashes into steam near the water level or in a part of the boiler whence the steam can ascend uninterruptedly to the steam space. In addition to the idea of non-circulation or of scanty circulation it is de- 20 manded that the boiler should be economical in consumption of fuel, should have a large amount of heating surface in proportion to its size, and also that it should be so arranged and shaped that it may be of 25 requisite strength if possible without the use of stays. The boiler now to be described embodies all these requisites. It consists of 30 a cylindrical shell *a a a* inclosing another cylinder *b b b* between which is a water 35 space, and in the lower part of the hollow or cavity of the inner cylinder is to be fitted a suitable grate and ash pit. Proper charging apertures, to be provided with suitable 40 doors are to be cut through both cylinders and around the apertures the inner and outer shells are to be connected, so as to prevent 45 the escape of water, in any usual or proper manner.

An annular plate *c c* is to be securely at- 45 tached to the upper end of the two cylinders, closing up the annular space between them. I deem it most important where horizontal tubes are used in a boiler, as water tubes, to counteract the equilibrium of pressure at 50 both ends of these, which equilibrium allows the steam to be held stationary in the center of the tubes and as the steam does not afford protection, the latter rapidly burns off. I aim to provide this protection, by cutting 55 off the direct communication with the steam chamber and thus by maintaining lower

temperature compel the action in one direction only. When the steam dome is of large size, its bottom plate will extend over the cavity of the inner cylinder, except an opening in the center, where this plate has a circular aperture. To the edge of this last named aperture is secured the top of a third cylinder *d d* which extends downward and is closed at bottom directly over the grate 60 bars. Numerous tubes *e e e* connect the interior of this last named cylinder with the annular water space, their ends being secured to the innermost and middle cylinders in any proper way. The annular space between the shell and the middle cylinder is to be closed at bottom and a series of holes *f f f* are to be cut into the outer shell just above the bottom of the annular space or at about the level of the lowest row of tubes; to these 70 holes proper pipes such as *g g g* are to be fitted, through which water may be forced into the boiler.

A dome shaped vessel such as *h h h* is to be fastened securely to the upper circular plate or to the outer cylinder, and from this dome is to extend a proper steam pipe and there are also to be fitted to this dome proper gage cocks or other means for ascertaining the level of the water. A safety valve may 80 be attached either to the steam pipe or the dome. Outside of this dome another dome such as *i i*, is to be secured provided with a passage such as *j* for the exit of smoke and into the lower part of this dome are to lead 85 a number of tubes such as *k k* which extend from the cavity of the middle cylinder through the annular water space. The inner dome must be sufficiently strong to resist the pressure of steam, the outer one need 90 only be as strong as an ordinary smoke pipe or stack.

Before firing up water is to be admitted into the boiler filling the annular space the tubes *e e e* the cavity of the innermost cylinder and rising a few inches into the bottom of the dome. When fire is made on the grate bars the gases will rise and burn between the middle and inner cylinders and around the tubes *e e e* will pass out through 100 the tubes *K K* into the space between the two domes and finally through the smoke pipe. The hottest part of the boiler will be the outer or fire surface of the innermost cylinder and those parts of the tubes nearest it. 105 The water, as fed in, will rise and go inward centripetally through the tubes, being more

and more heated, and will flash into steam partly in the cavity of the inner cylinder (whence it has free ascent into the steam space) and partly in the dome itself and 5 when there will be dried or partially superheated by the heat from the products of combustion passing up the space between the two domes.

From this description it will be perceived 10 that the boiler has a large heating surface, that the shell being a cylinder and the steam space being a dome need no stays, and that the middle cylinder will be prevented from collapsing by the tubes *e e e* which act 15 as stays. Vessels of other shape may be substituted for the two dome shaped vessels and they may be of smaller or greater diameter in proportion to the size of the shell; if the former the tubes *k k* may be replaced by 20 mere holes cut through the horizontal plate *c, c*, and when it is desired to provide a heater, the steam dome can be reduced in size as to allow the unabsorbed heat to pass upward, instead of laterally through the annular water chamber. Another dome sheet 25 will be added so as to inclose a water space

the base of which will correspond with the top of the annular chamber of the boiler; and the two plates that there form the heater will be riveted together at top, leaving a circular opening of the size of the chimney. As the unabsorbed heat will naturally impinge on the surface of the heater in its attempted escape to the chimney, the economy of this arrangement is sufficiently indicated.

Having described my boiler and its operation, I claim—

The arrangement described for promoting the centrifugal movement of the water and 40 the durability of the horizontal water tubes, by cutting off the direct communication between the steam chamber and end of the tubes nearest the feed pipe.

In testimony whereof I have hereunto subscribed my name in the town of Rome, Oneida Co., N. Y., on this 4th day of January A. D. 1860.

BENJAMIN H. WRIGHT.

In presence of—

J. HATHEWAY,
Wm. G. RILEY.
